NONREFILLABLE BOTTLE WITH A DETECTOR AND AN IMPELLER

Charles Fall, Montclair, N. J.

Application March 29, 1935, Serial No. 13,619

6 Claims. (Cl. 215—14)

This invention relates to a non-refillable bottle with a detector and an impeller.

The object of the invention is the production of a bottle for fluids which can not practically be refilled with a fluid.

The second object of the invention is the production of a bottle for fluids, provided with a detector which indicates the amount of the fluid poured therefrom when used.

10 The third object of the invention is the production of an automatic impeller for the bottle, to assist in driving its outlet mechanism.

In the accompanying drawings Fig. 1 represents a section as on the line 1—1 of Fig. 4 of a bottle indicated with enlarged dimensions; Fig. 2 shows a section of Fig. 1 on the line 2—2; Fig. 3 is a section of Fig. 1 on the line 3—3; Fig. 4 indicates a top view of Fig. 1; Fig. 5 represents a section of Fig. 1 on the line 5—5; Fig. 6 shows 20 a section of Fig. 1 on the line 6—6; Fig. 7 is a fragmentary portion of Fig. 1 with a modification; Fig. 8 represents a section of Fig. 7 on the line 8—8; Fig. 9 indicates in part a left hand side view and in part a longitudinal section of Fig. 1 25 on a reduced scale with a modification and Fig. 10 is a top view of Fig. 1 on a much reduced scale.

Referring to the drawings, the upper portion of the neck of a bottle, preferably of glass, is indicated at 20, and to which is connected by means of cement 21 the supplemental neck, preferably of glass, indicated in its entirety by the numeral 22. The said supplemental neck 22 comprises the cylindrical hood shaped housing

35 23, with the projecting portions 24 and 25, and the indicator projection 26. A cylindrical outlet duct 27 is shown in the housing 23. A spherical seat 28 is indicated at the upper portion of the duct 27 and at the lower portion of the housing 23 is shown the annular recess 29 with the upper face 30. The neck 20 extends into the recess 29 and its upper end bears against the face 30.

Curved protecting flanges 31 and 32 extend from the housing 23 into the duct 27 a little beyond the longitudinal axis of the latter, and a seat 34 is formed at the upper end of the duct 27.

The annular clamping flange 35, having the oppositely positioned openings 36, projects from the upper end of the housing 23. 50 The cap for the bottle is indicated in its entirety by the numeral 37, and comprises the cork disc 38, upon which is positioned the metallic disc 39. Upon the disc 39 is shown the strip 40, having the depending arms 41, and the latter terminate in the L shaped clamping flanges 42

with the inclined ends 43. Rivets 44 clamp together the discs 38, 39 and the strip 40. When the said cap 37 is to close the outlet end of the duct 27, the strip 40 is positioned so that the clamping flanges 42 are in line with the openings 36, and the disc 38 is brought to bear on the seat 34. The flanges 42 pass through the openings 36, and the cap 37 is then turned to position the flanges 42, so that they will bear against the lower face of the flange 35, to securely clamp the 10 cap 37 to said flange 35.

A propeller shaft 50 square in cross section is provided with the similar journal ends 51 and 52. A gear casing designated in its entirety by the numeral 55, and preferably of metal not affected by the fluid to be contained in the bottle, is shown in the cylindrical housing 23, for the journal end 51 and its coaxing elements. The casing 55 comprises the inner wall 56, the end wall 57, and the front wall 58 with the projecting sleeve 59 having the flange 60. The end wall 57 is fastened to the wall 56 after the appurtenances of the casing have been assembled. The journal end 51 is supported by the walls 56 and 58 of the upper portion of the casing 55 and has fastened thereto the wheel 62 with the one tooth 63. A cap 64 concentric with the journal end 51 is detachably fastened to the front wall 58. A flange disc 65 is fastened to the journal end 51.

A shaft 68 in the lower portion of the casing 30 55 has one end journaled in the wall 56. A flange disc 69 is detachably fastened to the shaft 68 and a cap 70 to enclose the disc 69 is detachably fastened to the wall 56.

A spur gear 74 is fastened to the shaft 68 and 35 has extending therefrom the detector pin 75. An adjustable hub 78 encircles the shaft 68, but is not fastened thereto. The shaft 68 and hub 78 extend through the flange 60. The hub 78 has extending therefrom the detector arm 80. A cap 40 81 is detachably fastened to the flange 60 by means of the screws 82. A recess 83 in the cap 81 supports the outer end of the hub 78. Screws 84 extend through the sleeve 59 and clamp the hub 78 with its arm 80 in different positions.

45 Openings 87 may be made in the wall 58 and an annular transparent cover 88 is fastened to the wall 58 over said openings 87, to be enabled to view the position of the detector arm 80. A pawl 90 is pivoted to the wall 56 and engages the 50 teeth of the spur gear 74. A spring 91 has one end bearing on the pawl 90 and its other end is fastened to the casing 55, so that the spur gear 74 can turn only in one direction indicated by the arrow A, Fig. 5.

A propeller 92 is shown with its hub 93 having the square opening 94, and the blades 95. The hub 93 is supported in the shaft 50. The peripheries of the blades 95 contact with the spherical 5 seat 28 and with the inner faces of the flanges 31 and 32 for a portion of each rotation of the propeller 92.

On the journal end 52 is fastened the small pinion 96. A second gear casing preferably of metal not affected by the fluid in the bottle, is designated in its entirety by the numeral 100, and is located in the neck 23. The casing 100 comprises the front wall 101, the end wall 102 and the rear wall 103. The wall 102 is fastened to 15 the wall 103 after the appurtenances thereof have been assembled. The journaled end 52 is journaled in the walls 101 and 103. A flange disc 105 is detachably fastened to the journal end 52 and bears against the wall 101. A cap 106 covers 20 the disc 105 and is detachably fastened to the wall 101. In the lower portion of the casing 100 is positioned the shaft 109, the ends of which are journaled in the walls 101 and 103. A flange disc 110 is fastened to one end of the shaft 109 25 and an hexagonal disc 111 is fastened to its other end. The discs 110 and 111 bear against their adjacent walls 103 and 101.

A spur gear 118 is fastened to the shaft 109 and meshes with the pinion 96. A spiral spring 30 118 has one end fastened to the shaft 109 and its other end is fastened to the wall 101 by means of the pin 118. A pawl 120 is pivoted to the wall 101 of the casing 100 and coacts with the teeth of spur gear 116. A spring 122 has one end fastened to the casing 100 and its other end bears 35 against the pawl 120. The tension of the spring 122 is slightly greater than the tension of the spring 118 to prevent the latter unwinding unless when required. The spiral spring 118 with its appurtenances coacts as an impeller for the propeller 92.

At the lower end of the duct 27 is secured a hinge plate 125 having the eye ends 126 from which extend the stop lugs 127. An outlet valve 45 130 having the inner edge 131 and the eye 132 is hinged to plate 125 by means of the hinge pin 134. A recess 135 with the seat 136 is shown in the housing 23 for the valve 130. When the valve 130 swings to its open position, not quite vertical, it abuts against the stop lugs 127 and thereby controls the extent of the swing of said valve.

Referring to Fig. 9, in which a modification is incorporated, the supplemental neck 22 for the bottle is dispensed with and it is indicated with 55 the neck 22a with its outlet duct 27a. From the upper portion of the neck 22a extends the clamping flange 35 and the strip for the cap is again indicated at 40 with its clamping flange 42. The upper wall of the bottle preferably of glass is shown at 149 which is integral with the neck 22a. The longitudinal wall of the bottle is shown at 141 and its bottom wall is shown at 142 with the opening 143 for the inset 144, which is held in place by cement.

60 It will be noted that when the mechanism of the gear casing 55 is placed therein the detector arm 80 is positioned to bear on the upper face of the detector pin 75, and then fastened in place by means of the screws 84. The spring 118 is wound up by turning the disc 111 with a wrench. After the mechanisms in both casings 55 and 65 100, and the propeller 92 have been assembled, the supplemental neck 22, or the neck 22a of glass is blown in place.

70 The bottle with the neck having the upper

portion 20 is filled before the supplemental neck 22 is fastened to the upper portion thereof, and the bottle having the neck 22a, can be filled through the opening 143 after which the inset 144 can be secured in place.

To pour the fluid from either form of bottle shown and described, the cap 37 is first removed. This is accomplished by turning said cap until the clamping flanges 42 are brought in line with the openings 36 of the flange 35, when the said cap 37 with its cork disc 38 can be easily lifted from the flange 35. The bottle is then tilted with the supplemental neck 22 or neck 22a inclining downwardly with the indicator projection 26 uppermost. In this position the outlet valve 130 15 will swing open until it abuts against the stop lugs 127 and the fluid as it flows from the bottle will strike the blades 95 of the propeller 92. The latter will turn in the direction of the arrow B, Fig. 2, and the fluid will flow out of the outlet end of the outlet duct 27. The flange 32 will prevent the fluid choking the propeller 92 and direct the fluid to flow in the direction of the arrow C, Fig. 2. With the rotation of the propeller 92 the shaft 50 and the wheel 62 with its tooth 63 are turned in 20 the direction of the arrow B, Fig. 5. For each revolution of the tooth 63, the spur gear 74 is turned the circumferential distance between a pair of its teeth in the direction of the arrow A, and the detector pin 75 is revolved the same angular distance from the detector arm 80. This is 25 repeated for each revolution of the propeller 92, until the detector pin 75 swings through an arc which positions it against the upper face of the arm 80.

The wheel 62 with its tooth 63 and the spur gear 30 74 are proportioned so that the bottle will be emptied of its fluid when the pin 75 bears against the lower face of the arm 80 and the propeller is 35 prevented from further turning.

Should any attempt be made to pour any fluid 40 into the bottle through the upper end of the duct 27, the propeller 92 would have to turn in a direction opposite to the arrow B, Fig. 2, and the spur gear 74 would have to turn in a direction 45 opposite to the arrow A Fig. 5. This would be prevented by the pawl 90. The fluid entering the bottle at the upper end of the duct 27 could not turn the propeller in the direction of the arrow B because the weight of water between the blades 50 95 on the side E Fig. 2 of the propeller would prevent it. Also the valve 130 would prevent fluid entering the bottle at the outlet end of the duct 27. It is also to be noted that the blades 95 of the propeller 92 contact with the flanges 31 and 55 32 for a portion of the rotation of said propeller, to produce closures between the propeller and said flanges.

During the rotations of the propeller 92 in the direction of the arrow B, the impact of the out 60 flowing fluid against the blades 95, overcomes the excess of tension of the spring 122 over the spiral spring 118, and the latter unwinds gradually to assist the turning of the spur gear 116 in the direction of the arrow G Fig. 6 and consequently the 65 propeller 92 in the direction of the arrow B, Fig. 2.

The spring 118 is of such proportions that it 70 will function as an impeller until the contents of the bottle has been poured out of the same.

It is to be noted that the non-refillable bottle 70 would be operative without the outlet valve 130, the detector arm 80 and its appurtenances, and the impeller with its spring 118 and its other appurtenances.

The impeller may be modified as indicated in 75

Figs. 7 and 8. In this modification instead of the journal end 52 there is provided for the propeller shaft 50 the journal end 52a. A hexagonal disc 111a is fastened to the journal end 52a. A gear housing is shown at 100a with the front wall 101a, the end wall 102a and the rear wall 103a. The walls 101a and 102a are connected to each other after the appurtenances therein have been assembled. The journal end 52a extends through the gear casing 100a and is journaled with walls 101a and 103a. A spur gear 146 is fastened to the journal end 52a. The spiral spring 118 has one end fastened to the wall 101a, by means of the pin 147 and its other end is fastened to the journal end 52a. A cap 148 covers the disc 111a and is fastened to the wall 101a. A pawl 149 is pivoted to the wall 103a and a spring 150 has one end bearing on the pawl 149 while its other end is fixed. The spring 118 is wound up by a wrench or key applied to the hexagonal disc 111a and the spur gear 146 is normally held in place by the pawl 149. The tension of the spring 150 is slightly in excess of the tension of the spring 118, to prevent the latter unwinding unless when required to unwind, that is to say when the fluid is poured from the bottle. The out flowing fluid strikes the blades of the propeller 92 and overcomes said excess tension and releases the spur gear 146. By this means the spring 118 is released and unwinds to impell the propeller 92 to turn it in the direction of the arrow B, Fig. 2.

The annular clamping flange 35 of the supplemental neck 22 and of the neck 22a may be modified by eliminating the openings 36. The cap 37 is then positioned in place by forcing the inclined ends 43 of the clamping flanges 42 over the flange 35 to locate the flanges 42 to bear up against them. By this means the cap 37 with cork 38 can be easily positioned in place. The cap 37 with its cork 38 can be easily pulled from the flange 35 to open the outlet duct 27 for the fluid to be poured from the bottle.

Attention is called to the fact that the detector pin 75 when it has made its revolution from one side of the detector arm 80 to the other, it functions as a signal to give notice that the bottle has been emptied.

Various modifications may be made in the invention and the present exemplification is to be taken as illustrative and not limitative thereof.

Having described my invention, I claim:

1. In a bottle having a fluid therein the combination of a neck having an outlet duct, a propeller positioned in said duct and journaled to said neck, said propeller turning with the impact of a fluid poured from the bottle, a detector pin revolving with the revolutions of the propeller and a detector arm in the path of the detector pin to stop the same, after revolving through a predetermined arc when the fluid of the bottle has been poured therefrom.

2. In a bottle having a fluid therein the combination of a neck having an outlet duct, a propeller wheel positioned in said duct and journaled to said neck, said propeller turned with the impact of the fluid poured from the bottle and an impeller coacting with said propeller to enhance its revolutions as the fluid is poured from the bottle.

3. In a bottle for a fluid the combination of a

neck having an outlet duct, a shaft extending through said duct, journal ends for the shaft extending into said neck, a propeller supported on said shaft and turning therewith when the fluid is poured from the bottle, a wheel having one tooth fastened to one of said journal ends, a spur gear journaled below said wheel having one tooth, adapted to have its teeth in mesh with said one tooth, said spur gear turning through a small arc for each revolution of the wheel having one tooth, a detector pin extending from said spur gear, and a normally stationary detector arm in the path of said detector pin, said pin bearing against said arm after said spur gear has turned through a predetermined arc to function as a signal that the contents of the bottle have been poured therefrom.

4. In a bottle for a fluid the combination of a neck having an outlet duct, a propeller positioned in said duct and journaled to said neck, said propeller turning with the impact of the fluid as it is poured out of the bottle, means to maintain the rotation of said propeller in one direction and a curved flange extending from one side of said duct at its outlet end over and adjacent to the periphery of said propeller and extending beyond the longitudinal axis of said duct to direct any fluid entering said duct on the side of the propeller opposite said flange to stop the rotations of said propeller, said flange functioning as a closure for the propeller as the blades thereof move under the flange.

5. In a bottle for a fluid the combination of a neck having an outlet duct, a propeller positioned in said duct and journaled to said neck, said propeller turning with the impact of the fluid as it is poured out of the bottle, means to maintain the rotation of said propeller in one direction, and a curved flange extending from one side of said duct below and adjacent to the periphery of the propeller and beyond the longitudinal axis of the duct to prevent said propeller from being choked as the fluid is poured therefrom, said flange functioning as a closure for the propeller as the blades thereof move over said flange.

6. In a bottle for a fluid the combination of a neck having an outlet duct, a shaft extending through said duct, journal ends for the shaft extending into said neck, a propeller in said duct supported on said shaft, a pinion fastened to one of said journal ends, a shaft spaced from the latter journal end, a spur gear fastened to the latter shaft and in mesh with said pinion, a spiral spring having one end fastened to said shaft and its other end fixed in said neck, a pawl adapted to engage the teeth of said spur gear to stop rotation of the latter, and a spring having one end fixed in said neck and its other end bearing against said pawl to maintain it in mesh with said spur gear, the tension of the latter spring being somewhat in excess of the tension of said spiral spring, the fluid as it is poured out of the bottle striking the blades of the propeller for its rotation, to turn said spur gear and thereby releasing said spiral spring, for the latter to enhance the rotation of the spur and consequently assisting to turn the propeller as the fluid is poured from the bottle.
